UNITED STATES PATENT OFFICE.

AMBROSE A. DEAN, OF KANSAS CITY, MISSOURI.

DESIGN FOR A DECK OF PLAYING CARDS.

Application filed June 21, 1923. Serial No. 6,542. Term of patent 14 years.

To all whom it may concern:

Be it known that I, AMBROSE A. DEAN, a citizen of the United States, residing at Kansas City, in the county of Jackson and State of Missouri, have invented a new, original, and ornamental Design for a Deck of Playing Cards, of which the following is a specification, reference being had to the accompanying drawings, forming part thereof.

Figs. 1, 2, 3 and 4 are views of the "King" cards of the four suits, showing my new design.

Figs. 5, 6, 7 and 8 are views showing the "Queen" cards of the suits.

Figs. 9, 10, 11 and 12 are views showing the "Jack" cards of the suits.

Figs. 13 to 22 inclusive are views of the ace and spot or "pip" cards of the "spade" suit.

I claim:—

The ornamental design for a deck of playing cards, as shown.

AMBROSE A. DEAN.
